UNITED STATES PATENT OFFICE

WILFRID J. LEMIEUX AND JAMES HOOD, OF NEW BEDFORD, MASSACHUSETTS, AS
SIGNERS TO BEACON MANUFACTURING COMPANY, OF NEW BEDFORD, MASSACHU-
SETTS, A CORPORATION OF MASSACHUSETTS

AUTOMATIC LOOM

Application filed October 29, 1928. Serial No. 315,824.

This invention relates to automatic filling-replenishing looms and particularly to box-motion looms employing shifting shuttle boxes at one end of the lay for changing the color of the filling. The present invention is directed to means for selectively replenishing the filling in a plurality of shuttles upon the substantial exhaustion of the filling in any one of them.

10 One object of the invention is to provide an automatic filling-replenishing mechanism for looms employed in weaving fabrics with ombré effects or patterns wherein the dark and light portions of the filling-yarns contributing to the pattern are disposed in register either in contrasting relation or with any other particular association of the different shades of color.

Another object of the invention is to provide automatically-operated means for replenishing the filling in any two or more selected shuttles carrying filling of certain kinds to be matched or registered in the pattern being woven.

25 Another object of the invention is to provide control-means operative when the filling is substantially exhausted in one of the shuttles contributing to the pattern to subsequently change the filling in another associated shuttle as the latter becomes active without waiting for the substantial exhaustion of the filling in this shuttle.

Another object of the invention is to provide a device of the type specified which may be applied to use with automatic looms of standard type without material alteration in the filling-replenishing mechanism thereof.

35 Another object of the invention is to provide a device of the type specified which is simple in construction, positive in action and efficient in operation without liability of the mechanism becoming deranged or getting out of order.

40 Further objects of the invention are set forth in the following specification which describes a preferred form of construction of the device, by way of example only, as illustrated by the accompanying drawings. In the drawings:

50 Fig. 1 is a perspective view showing the

filling-replenishing mechanism at the magazine end of the loom and the present improved control-device applied to use therewith;

Fig. 2 is a plan view showing one side of the loom magazine and illustrating the present improved control-device for the filling-replenishing mechanism in its relation thereto;

Fig. 3 is a similar view showing the control-device in a different position of operation;

Fig. 4 is a similar view showing the control-device in a still different position of operation;

Fig. 5 is a sectional elevation of the magazine showing the vertical slides of the filling-replenishing mechanism and illustrating the present control-device in operative relation therewith;

Fig. 6 is a similar view showing the control-device in a different position of operation;

Fig. 7 is a similar view showing the control-device in a still different operative relation;

Fig. 8 is a plan view of the main operating element of the control-device;

Fig. 9 is an enlarged perspective view of the same;

Fig. 10 is a detailed view of the inside of the magazine showing the filling-transferring means in one position of operation;

Fig. 11 is a similar view showing the filling-transferring means in a different position after the delivery of a bobbin or filling-carrier to the giveways of the magazine;

Fig. 12 is a view of a bobbin or filling-carrier containing ombré colored yarn and illustrating one manner in which the yarn is wound with the dark-shaded portion at the center of the bobbin; and

Fig. 13 illustrates a bobbin with the dark-shaded portions of yarn at its ends.

In weaving blankets and other fabrics having jacquard stripes or patterns, and in producing similar effects on looms with dobby motions, it is a preferred practice to form the stripes or patterns from yarns dyed in ombré colors or shades, that is with the color shading from light to dark and back to light again. To obtain pleasing contrasts and artistic effects the filling yarns contributing to

the pattern are sometimes woven with the dark shade of one color opposed to the light shade of a contrasting color, or in other instances the light shades of two colors may run counter and the dark shades be associated in register, as the case may be.

Blankets and other fabrics of this type are usually woven on Jacquard or dobby-motion looms and for the sake of economy in the cost of manufacturing, the goods are preferably produced on automatic looms embodying filling-replenishing mechanism. Such types of looms have shifting or changing shuttle boxes at one end of the lay which are operated to change the color of the filling in accordance with the pattern controlled by the jacquard or dobby head; the filling-replenishing mechanism being arranged at the opposite end of the loom to operate to supply fresh bobbins or filling-carriers to the shuttles when the filling therein becomes substantially exhausted.

The filling-carriers or bobbins supplied to the shuttles do not invariably contain the same amount of yarn, that is to say, different bobbins may have a greater or less length of yarn spun or wound thereon in accordance with conditions of the winding or spinning, and also as affected by the handling of the bobbins before they are placed in the loom magazine. It is therefore obvious that the filling on one bobbin may run out or become exhausted sooner than that on another, so that where two or more bobbins are used to introduce the ombré shaded portions of the yarn in register in the pattern the disposition of the colors will not be properly regulated if one bobbin of a certain color is exhausted and the filling replenished in the shuttle without immediately changing the filling in the next shuttle becoming active.

Stated briefly, if the filling is not replenished in both shuttles carrying the contrasting colors at substantially the same point the ombré shades of the colors will not register properly and the pattern being produced will have a blurred or irregular effect.

To avoid this mismatching or incorrect register of the colors in the pattern we have devised means operating in connection with the filling-replenishing mechanism of the automatic loom whereby to control the time of replenishment of the different shuttles so that when new filling is supplied to one particular shuttle it will subsequently be supplied to a related shuttle immediately the latter becomes active, or at the proper point to insure the desired disposition of the colors woven into the pattern of the goods.

A preferred embodiment of the control device or regulating means for the filling-replenishing mechanism of a standard type of loom is illustrated in the accompanying drawings as comprising a combination of elements as next described.

Fig. 1 of the drawings illustrates a well known type of filling-replenishment mechanism as viewed from the front of the loom looking toward the back of the magazine. The magazine is mounted on the breast-beam at the right-hand side of the loom and comprises opposite upright frame-members 2 and 3 provided with vertical guideways which form compartments or cells 4 for receiving the ends of the bobbins or filling-carriers *b*, see also Figs. 2 to 4, 5 to 7 and 10 and 11. In the present drawings the magazine is illustrated as provided with four compartments or cells for containing bobbins carrying yarn in four different colors. The bobbins *b* are stacked in the magazine with their heads in the guideways or cells of the frame-member 2 and their tips in the cells of the opposite frame 3, being arranged as to their colors in accordance with the sequence of operation of the shuttle boxes. It will be understood that the bobbins are delivered singly from the magazine to be transferred to an operative shuttle as the filling therein becomes substantially exhausted, each bobbin being first released from its cell in the magazine to drop down onto giveways which hold it in position above the shuttle until the transerrer acts to force it down thereinto.

Referring more particularly to Figs. 10 and 11 of the drawings, the bottom of the magazine frame-members 2 and 3 are formed with inclined flanges 5 onto which the bobbins drop as they are released from their cells, whereby they are fed down onto the giveways 6 into transferring position above the shuttle *S*. The giveways 6 consist of rockable arms or levers pivoted at 7 and provided at their outer ends with rounded faces on which the bobbins *b* rest as shown in Fig. 11. The giveways 6 are normally held in raised position as illustrated in Fig. 11 under the tension of suitable springs, not herein shown, whereby they are adapted to yield and open as the bobbin *b* is carried down into the shuttle *S* under the action of the transerrer 10 to be later described.

The bobbins *b* are normally held in stacked relation in the cells 4 with the lowermost one in each series resting on a pivoted cradle 11 which is operative to release the bobbins one at a time. Figs. 10 and 11 illustrate the cradles 11 as of the rolling type comprising arcuate cam-sections 12 which support the head and tip of the bobbins at their opposite ends. The cradles 11 are pivoted at 13 to adapt them to be turned to release the lowermost bobbin in the cell, the cam-section 12 being so shaped that with its first movement to one side of the bobbin will drop down into engagement with the concaved portion thereof as shown at the left in Fig. 10. When the cradle is rocked back to first position again the bobbin resting in its hollow will be released therefrom.

and the upper edge of the cam-section 12 will engage beneath the next lowermost bobbin in the series as shown at the right in Fig. 10, the construction and method of operation of the cradles being as well known to those versed in the art.

The cradles 11 are operated from a series of vertical slides 15, one for each cradle, arranged at the back of the frame-member 2 of the magazine opposite the cells 4. The slides 15 are slidably mounted on the face of the frame-member 2 and held in place by guides 16 straddling them in pairs at their upper ends, and individual guides 17 and 18 at the bottom, see Fig. 1. The slides 15 are formed with enlargements at their lower ends, in which are L-shaped cam-slots 20. The cam-slots 20 are engaged by crank-pins 21, see Figs. 1, 10 and 11, which project from crank-arms 22 connected with the pivots of the cradles 11, see Fig. 1. It will thus be seen that with a cradle 11 in the position shown at the right in Fig. 10, when its connected slide 15 is moved upwardly the crank-pin 21 will be caused to follow the cam-groove 20 to rock the cradle into reverse position as shown at the left in Fig. 10, the method of operation of these parts being more fully explained hereinafter.

The slides 15 are provided with forwardly extending fingers or projections 23 and 24 adapted to be engaged by a control-lever, to be later described, to slide them up and down to actuate the rolling cradles 11. The slides 15 are maintained in the upper and lower positions to which they are shifted by means of spring-plungers or detents 25 slidable in the upper guides 16 and formed with beveled ends engaging suitable notches 26 and 27 in the slides, see Figs. 5, 6 and 7.

The slides 15 carry spring-catches or latches 30 at their upper ends adapted to cooperate with certain parts of the bobbin-transferring means to be later described. As shown in Fig. 1 of the drawings, the slides 15 are slotted at 19 and the latches 30, which are of substantially triangular shape, are pivoted in the slots on pins 31 extending through the sides thereof. The points of the latches 30 are urged forward under the tension of suitable springs indicated at 32 in Fig. 1, but not herein shown in detail as the construction of this part of the device is well known to those versed in the art. The latches 30 have rounded or cam-shaped rearward edges, indicated at 33 in Fig. 1, which are adapted to ride against the face of the frame-member 2 of the magazine when the slides 15 are carried downward to withdraw the points of the latches into position flush with the front of the slides. It will be noted from Fig. 1 that the frame-member 2 is provided with a series of elongated openings or slots 8 disposed in alinement with the several slides 15. When any one of the slides is

carried into raised position, as represented by the showing of the left-hand slide in Fig. 1, the cam-shaped edge 33 on the latch 30 will ride off from the face of the frame-member 2 as the upper end of the slide comes opposite its respective slot 8 and thus the latch is released to allow the spring 32 to move it into forward or active position. During the next downward stroke of the slide 15 the latch will act to rock the setting-lever 35 to raise the transfer-dog into position to be struck by the bunter on the lay to effect the transfer of the bobbin from the giveways into the shuttle, the mechanism for performing these functions being as next described.

The setting-lever 35 is of yoke-like construction comprising opposite arms 36 connected by a cross-strip, this lever being mounted fast on a cross-shaft 37 and secured thereto by means of set-screws 38 in its arms 36. The shaft 37 is mounted free to turn in bearings 39 projecting from the frame-member 2 and at its right-hand end, as viewed in Fig. 1, it carries a lever 40 secured fast thereon. The lever 40 carries a pin 41 engaging a slot 42 in a bell-crank lever 43 which is pivoted to rock on a stud 44 projecting from the side of the frame-member 2. The opposite arm of the bell-crank lever 43 carries a pin 45, to which is connected the end-piece 46 of a rod or link 47. It will be understood that as the setting-lever 35 is rocked downwardly through the engagement of the latch 30 on the slide 15 with its cross-bar it will turn the lever 40 to rock the bell-crank lever 43 whereby to raise the link or rod 47. The rod 47 is connected to lift the transfer-dog, not herein shown or described as it may be of any usual construction as generally employed on looms of the present type.

The raising and lowering of the slides 15 is effected selectively through the action of a control-lever 50 carried on an oscillating and sliding shaft 51. The shaft 51 is mounted in bearings 53 and 54 formed as a part of the frame-member 2 and at its left-hand end, as viewed in Fig. 1, it carries a circumferentially grooved sleeve or collar 55, see Figs. 2, 3 and 4. The shaft 51 is slid in its bearings 53 and 54 under the action of a bell-crank lever 56 operative from suitable means connected with the box-motion of the loom. The upright arm of the bell-crank lever 56 carries a stud 57 engaging a peripheral groove 58 in the collar 55, previously referred to, and the other arm of this lever, indicated by dotted lines in Fig. 1, is suitably connected to the shaft which operates the box-motion to shift the shuttle boxes to change the color of the filling. A spring 59 acts to draw the bell-crank lever 56 upwardly, these connections not being herein shown or described in detail as they are of well known construction and in general use on looms of the present type. Suffice it to state that the bell-crank 130

lever 56 is operated synchronously with the shifting of the shuttle boxes to slide the color-control shaft 51 in its bearings whereby to adjust the control-lever 50 into position to 5 operate selectively on the several slides 15 which initiate the transfer of the bobbins to the appropriate shuttles carrying the same kind of filling.

The control-lever 50, shown in perspective 10 view in Fig. 9, is in the form of a yoke having two parallel arms 60 and 61 formed with hubs 62 which are secured fast on the shaft 51 by means of set-screws 63. The arms 60 and 61 are connected by a cross-bar 64 which is extended at one end in an arm 65 provided on its forward side with a longitudinal rib or spline 66. The spline 66 is adapted to slide in a slot 67 at the forward end of a lever 68, see Figs. 5, 6 and 7, which is pivoted on the 15 shaft 51 between the sides of its right-hand bearing 54. The lever 68 is formed with depending fingers 69 in which is mounted a slideable plunger 70 carrying a coil spring 71 for urging the end of the plunger against the 20 web or arm 72 of the bearing 54, thus tending to rock the lever 68 upwardly.

Connected to the outer end of the lever 68 by means of a pin 73 is a rod or link 74 terminating at its lower end and in a turnbuckle 30 75. The turnbuckle 75 is connected by a pin 76 to the chopper-lever 77, this part not being herein shown in detail as it is of well known construction. The usual slide-block 79 is operated by a cam on the bottom shaft 35 of the loom, not herein shown, to be constantly reciprocated in a vertical path. The slide-block 79 is connected to the chopper 77 by means of a pin 80, these parts being indicated in Fig. 1 but not shown in detail. The free 40 end of the chopper 77 moves up and down in the chopper-slot unless its motion is arrested by the presence of the feeler indicator pin across its slot, which condition is brought about by the operation of the filling-detector 45 when the filling on the bobbin is nearly exhausted. Any usual type of filling-detector may be employed on the loom and this device operates the feeler-detector pin to slide the latter across the chopper-slot, the pin acting 50 as a temporary fulcrum to arrest the downward motion of the free end of the chopper-lever to cause the slide-block 79 to act to pull down on the rod or link 74. The downward movement of the rod 74 rocks the lever 55 68 downward against the action of its spring-plunger 70 and through its connection with the rib or spline 66 on the lever 50 the latter is rocked to raise its arms 60 and 61 in the manner as illustrated in Figs. 5 and 7. The 60 arms 60 and 61 on the lever 50 are adapted to engage the upper projections or fingers 23 on the slides 15 to effect the raising of the slides, it being hereinafter more fully explained how the lever 50 is shifted with the 65 shaft 51 to bring its arms 60 and 61 into reg-

ister with the respective projections on the different slides 15 in accordance with the selection of different colored bobbins to be transferred to the appropriate shuttles.

Heretofore in devices of the present type 70 the control-lever 50 has been arranged and operated to lift only one slide at a time, being shifted back and forth as required under the action of the bell-crank lever 56 which moves in synchrony with the changing shuttle boxes 75 so as to effect the change of filling in accordance with the color running in the active shuttle. As a feature of the present invention we have devised simple and ingenious means for regulating the action of the control-lever 80 50 to lift a plurality of slides 15 at one time whereby two or more bobbins of selected colors in the magazine may be placed in condition for release. The object of this arrangement is to provide that when one of these bobbins is transferred to its respective shuttle the other bobbin will be transferred to its shuttle immediately the latter is called in order that the different kinds of filling may continue to be properly related in the pattern as more 85 fully explained hereinafter. For this purpose one or both of the arms 60 and 61 of the control-lever 50 may be provided with a latch-like pawl 85 pivoted to its side as shown in Fig. 9. Where only two of the colors in 90 the pattern are required to be placed definitely in register a single latch or pawl 85 is employed, but where all of the four different colors of filling must be properly associated in the pattern we employ a latch on each arm 95 100 60 and 61 as shown in Fig. 8. Since the method of operation of both latches is the same, for the sake of brevity it will be sufficient to describe the arrangement of one of them.

As shown in Figs. 2 to 4 and 9, the latch 85 is pivoted on a screw 86 screwed into the side of the arm 61 of the lever 50 and at its outer end it carries a flat plate 87 resting across the top of the arm. It will be observed by reference to Figs. 2 and 3 that whenever the arm 61 is in alignment with either of the pair of right-hand slides 15 the plate 87 on the latch 85 will be positioned across or in overlapping relation with the fingers 23 on both of the 110 slides; it being noted that the finger 23 on the right-hand slide 15 is offset to the left, as shown more clearly in Fig. 1, to bring it into closer relation with the finger 23 on the next adjoining slide. This same arrangement may be put into effect with reference to the left-hand pair of slides 15, and preferably the finger 23 on one of the slides is widened at the side, as indicated at 29 in Figs. 2 and 3, to bridge the space between the fingers when it 115 is desired to operate two slides in unison. The method of operation of the lever 50 to raise the two slides 15 is more fully explained hereinafter.

The control-lever 50 is rocked in the oppo- 120 125 130

site direction to carry its arms 60 and 61 downwardly whereby to lower the slides 15 to release the bobbin after the initial movement of the cradle has been effected by the upward movement of the slides. It is obvious that only one bobbin can be transferred at a time since only one shuttle is in the single box at the magazine end of the loom at the finish of a pick in this direction. Therefore, the slides 15 must be lowered individually in accordance with the selective control of the color-motion operating in harmony with the box-motion. The downward movement of the slides 15 is effected by the engagement of one or the other 15 of the arms 60, 61 with the lower fingers 24 on the slides as the control-lever is rocked in a clockwise direction from the chopper-lever 77. This individual actuation of the slides 15 to lower them is provided for by the pawl-like action of the latch 85. That is to say, when the cross-member or plate 87 on the latch 85 comes into engagement with a finger 24 on a slide 61 adjacent to the slide being operated upon the latch will be tilted upwardly as shown in Fig. 6 so that it will have no effect in moving this slide; it being understood that the arm 61 engages positively with the finger 24 on the next adjacent slide as shown in Fig. 6 to carry this slide downwardly.

The color-control device for the filling-changing mechanism having now been described in detail it only remains to refer to the transfer-mechanism which is operated therefrom. In Fig. 1 of the drawings the transfer-lever 90 is shown as arranged with the transfer-dog 10 at its end adapted to slide through a slot 91 in the frame-member 2 of the magazine, see also Fig. 10. The transfer-lever 90 is pivoted at 92 and controlled by a coil spring 93 which normally holds it in raised position. A bunter 94 on the lay of the loom strikes a suitable dog, not herein shown, which is pivoted to a right-angled arm on the transfer-lever and adapted to be raised into position by the rod 47 operated from the bell-crank lever 43 previously referred to. These parts are not herein shown and described in detail as they are of usual construction and well known to those versed in the art.

The method of operation of the complete device will now be explained with reference to the action of the color-control in transferring two filling bobbins of related colors to insure their proper register in the pattern being produced.

During the normal operation of the loom as the shuttle boxes are shifted to change the color of the filling the bell-crank lever 56 is rocked in synchrony with the box-motion to slide the shaft 51 whereby to adjust the position of the control-lever 50. The control-lever 50 is shifted at each change of shuttles to bring one of its arms 60, 61 into register with the finger 23 on the appropriate slide 15

opposite the magazine cell containing bobbins of a color corresponding to that in the called shuttle. Meanwhile the chopper-block 79 is continuously reciprocated and its motion is transmitted to the chopper-lever 77 to intermittently raise and lower the free end thereof. Each time the shuttle boxes at the magazine end of the loom and the lay moves forward to beat up the filling the feeler enters the side of the shuttle to indicate the condition of the filling on the running bobbin. Eventually, when the filling on a bobbin is substantially exhausted, the feeler will operate to carry the indicator pin across the chopper-slot whereby it acts as a fulcrum for the chopper-lever 77. This action takes place with the chopper-lever 77 in the upper part of the slot after its free end has been raised by the slide-block 79, so that at the next downward movement of the block the opposite end of the chopper-lever 77 which is connected to the turnbuckle 75 will be drawn downwardly to pull on the rod 74. The pull on the rod 74 rocks the control-lever 50 to raise its arms 60 and 61 and, through the engagement of one or the other of these arms with the finger 23 on one of the slides 15, this slide will be raised to actuate a cradle 11 to initiate the release of a bobbin from the cell controlled by this cradle.

It has been stated that heretofore in looms of the present type the control-lever 50 is operated to raise the slides 15 one at a time, but as provided by the present invention the control-lever 50 acts to lift a pair of slides for the purpose as now explained. For the sake of simplicity it will be sufficient to explain the action of the control-lever 50 on the right-hand pair of slides 15. Let it be assumed that the filling on the bobbins in the two cells of the magazine controlled by this pair of slides is in two different colors in ombré shades as used to produce a contrast in the pattern of the weave. For instance, one bobbin *b* may contain yarn of a certain color wound as shown in Fig. 12 with the dark portions of the yarn at the center of the bobbin and this type of bobbin may be supplied by the first or nearest cell of the magazine as viewed in Fig. 1. The second cell in the magazine may contain bobbins wound with a different color with the dark shaded portion of the yarn at the ends of the bobbin as shown in Fig. 13. As an example, the first bobbin *b* may carry green yarn shading from light at the ends of the bobbin to dark at its center and the bobbin *b'*, illustrated in Fig. 13, may be wound with red yarn shading from dark at its ends to light at the center. As illustrative of the use to which the present invention is applied a pattern of ombré stripes of alternating colors may be taken as an example. In such patterns the stripes run longitudinally of the cloth and the contrasting colors shade from

dark to light and light to dark again at short intervals. With the colors previously selected by way of example, the green stripes will alternate with red strips and the ombre shading will be disposed with the dark shades of green appearing opposite to or in register with the light shades of red.

In weaving patterns with this or any similar contrasting effect of colors the shuttles 10 are changed at the completion of each pick back to the drop-box end of the loom, there being not more than two successive picks from any one shuttle. Assuming that the shuttle carrying the bobbin with green filling 15 is running and that the feeler indicates the practical exhaustion of the filling as the shuttle is boxed at the magazine end of the loom then the filling-replenishing mechanism will be set in operation as follows: When this particular shuttle is called the shaft 51 is shifted 20 into the position illustrated in Fig. 2 of the drawings to carry the arm 61 on the control-lever 50 into register with the finger 23 on the first slide 15 controlling the cell supplied 25 with green bobbins. Consequently, when the chopper-lever 77 is operated to draw down the rod 74 to rock the lever 50 both slides 15 of the right-hand pair will be moved upwardly as indicated in Fig. 5. That is to say, with the arm 61 in register with the finger 23 on the right-hand slide 15 the plate 87 of the latch 85 will extend beyond the side of this particular finger and engage beneath the finger 23 on the next adjoining or second 30 slide 15 as shown in Fig. 2. The effect of this action of the control-lever 50 on the right-hand pair of slides 15 is illustrated graphically in Fig. 10, it being noted that the magazine is here shown as viewed from the 35 opposite direction from that in Fig. 1 so that the first two cells are at the left. As the two slides 15 are raised to the position shown at the left in Fig. 10 the cradles 11 are rocked from first position, shown at the 40 right in this view, to allow the two lowermost bobbins to drop down into the hollow of the cradles in position to be completely released at the next action of one or the other of their respective slides.

50 It is to be understood that the control-lever 50 is also rendered operative to raise both slides 15 of the first pair when the shuttle carrying the secondary color is operative. For instance, when the shuttle carrying the red filling is active the lever 50 is in the position shown in Fig. 3 with its arm 61 in register with the finger 23 on the second slide 15. With the lever 50 in this latter position the plate 87 will extend beyond the 55 arm 61 to overlap and engage beneath the extension 29 on the lug 23 of the first slide 15. Considering for the present, however, that the shuttle carrying the green bobbin is operative and that the feeler has indicated substantial exhaustion of the filling, and assum-

ing that both of the right-hand pairs of slides 15 have been moved to elevated position as previously explained, the next sequence of operations is as follows:

The shuttle containing green filling is picked to the drop-box end of the loom as the first pair of slides 15 are simultaneously raised to turn their respective cradles 11 into the position shown at the left in Fig. 10. As this first shuttle reaches the drop-box end of the loom it is replaced by a shuttle carrying red filling and this shuttle immediately makes a pick to the magazine end of the loom. During this change of shuttles the control-lever 50 is shifted from the position shown in Fig. 2 to that illustrated in Fig. 3 to bring its arm 61 in register with the second slide 15 controlling the cell containing the red bobbins b'. As the shuttle containing the red bobbin is picked to the magazine end of the loom the control-lever 50 is rocked from the rod 74 to carry its arm 61 downwardly to engage it with the lower finger 24 on the second slide 15 to push this slide downwardly. As the lever 50 depresses the second slide 15 the first slide will remain in raised position with the pawl 85 on the arm 61 lifted as shown in Fig. 6. The downward movement of the second slide 15 turns the cradle 11 controlled thereby back into first position as shown in Fig. 11, and thereby releases the lowermost red bobbin b' to allow it to drop down onto the giveways 6. This bobbin is now immediately transferred to the shuttle in the manner as next explained.

As the slide 15 is moved downwardly the latch 30 at its upper end engages the cross-bar on the setting-lever 35 to rock the latter in a clockwise direction; it being understood that the latch 30 is released to swing outwardly from the front of the slide 15 as the latter is raised to bring the latch into position opposite the opening 8 in the frame-member 2. For convenience of illustration in Fig. 1, and to prevent obscuring the view of the essential parts of the mechanism, the rearmost slide is shown in raised position in this view with its latch 30 released instead of illustrating the parts in a relation corresponding to the present explanation.

As the setting-lever 35 is rocked in the manner as last noted it turns the connected bell-crank lever 43 to pull the rod 47 upwardly. As the rod 47 is drawn upwardly it raises the transfer-dog, not herein illustrated, into position to be struck by the bunter 94, shown in Fig. 1, as the lay completes its forward stroke. As the transfer-dog is struck by the bunter it rocks the transfer-lever 90 to carry the transerrer 10 downwardly against the bobbin b', see Fig. 11, to transfer the latter to the shuttle S as the giveways 6 yield for this purpose. As the bobbin b' enters the shuttle it displaces the substantially exhausted bobbin therefrom,

the transfer operation being performed in the manner as well known to those skilled in the art.

The shuttle carrying the red bobbin b' now makes a single pick back to the drop-box end of the loom and is changed to substitute the shuttle carrying the green bobbin. Then as this shuttle, carrying the bobbin which has previously indicated depletion of filling, reaches the magazine end of the loom at its first pick a fresh green bobbin is transferred thereinto, it being understood that during the change of shuttles the control-lever 50 has been shifted back into position with its arm 61 in register with the first slide 15 controlling the cell containing green bobbins. The transfer of the fresh green bobbin to the last active shuttle is made in the same manner as with the red bobbin, that is to say the downward rocking motion of the control-lever 50 causes the depression of the slide 15 to again actuate the setting-lever 35 to raise the transfer-dog into position to be struck by the bunter as the lay beats up the filling.

It will be understood that the operation of the control-lever 50 to depress the slides 15 is effected by the chopper-lever 77 as its free end is detained at the upper end of the chopper-slot. The free end of the chopper-lever is moved upwardly by the slide-block 79 at each stroke of the latter until this end of the lever reaches the end of the slot, whereupon the opposite end of the lever 77 connected to the link 74 will be carried upwardly to give the control-lever 50 a relatively short stroke from its mean horizontal position to the position shown in Fig. 6. In other words, the control-lever 50 is normally operated continuously with a half stroke to carry its arm 61 down during each pick of any shuttle to the magazine end of the loom as is common in looms of the present type. Therefore, it will be apparent that since in the example of the operation of the device as above explained the control-lever 50 acts upon the depletion of filling in either of the two shuttles carrying red and green yarn to raise both slides 15 which initiate the change of filling in these shuttles, each of these slides will thereafter be moved downwardly to complete the transfer of the bobbins at subsequent half strokes of the control-lever. After a fresh bobbin has been transferred to the shuttle carrying red filling the control-lever 50 is shifted longitudinally, as before noted, to carry its arm 61 into position opposite the first slide 15 controlling the cell containing green bobbins. Then as the control-lever 50 is rocked in a clockwise direction on the next upstroke of the rod 74 its arm 61 moves the first slide 15 downwardly so that the latch 30 at the upper end thereof engages the setting-lever 35 to rock the latter downwardly. The setting-lever 35 is thus caused to act through the arm or lever 40 to rock the bell-crank lever

43 to raise the rod 47 and thereby lift the transfer-dog into position to be struck by the bunter 94. As the lay swings forward the transfer-dog is struck by the bunter to rock the transfer-lever 90 to swing the transferrer 70 down against the green bobbin on the give-ways to force it into the appropriate shuttle which is boxed at the magazine end of the loom; this sequence of operations being identical with that first described in connection with the transfer of the red bobbin. It has been mentioned that the half stroke of the control-lever 50 from horizontal to down position is continuous, the spring-plunger 70 restraining it from tilting upwardly as the chopper-lever 77 is moved bodily downward, but each time the free end of the chopper-lever is raised against the upper end of the chopper-slot its forward end is rocked upwardly and hence the rod 74 is caused to actuate the control-lever 50 in the manner as explained.

The filling-replenishing mechanism is reset by returning the setting-lever 35 to first position through the action of the transfer-dog in accordance with the usual functioning of these parts. As the lay moves back after the transfer operation the transfer-dog drops down out of the way of the bunter and operates with a cam action to pull the rod 47 downwardly. This pull on the rod 47 turns the bell-crank lever 43 to rock the setting-lever 35 upwardly into the position shown in Fig. 1. It is here noted that after the latch 30 on the descending slide 15 has acted to rock the setting-lever 35 during the transfer operation the engagement of the cam-portion 33 of the latch with the face of the frame-member 2 withdraws the latch into the slot 19 at the top of the slide to permit the return of the setting-lever 35 to first position as above explained.

The present drawings illustrate a four-color magazine and it is to be understood that while the control-lever 50 has been described as arranged to control the transfer of the bobbins in the first two cells only, the invention may also be utilized for controlling the transfer of the bobbins from the third and fourth cells when it is required to accurately register the other colors in the pattern of the weave. That is to say, with patterns of more complicated nature than the stripe effect herein used as an example, the colors in all four cells of the magazine may be controlled to register the ombré portions of the yarn. In other cases where two colors of ombré shaded yarns are used in one pair of cells, the other cells may contain bobbins in plain colors and these latter will be supplied to the shuttles in the regular way without the dual control. Where both pairs of cells contain colors in ombré shades the control-lever 50 is constructed as shown in Fig. 8 with a pawl or latch 85 on each of its arms 60, 61.

When it is not required to match or register the colors in one or both of the pairs of cells of the magazine one or both latches 85 may be turned back as shown in Fig. 7 so that the control-lever will operate in the usual manner to replenish the filling in each shuttle upon indication of depletion without reference to the requirements of the other shuttles.

It will be observed that our invention provides a particularly ingenious means for controlling the transfer of filling to the associated shuttles to insure a proper matching or register of the colors in the pattern of the weave. Its use on automatic looms results in a much clearer and more exact definition of the pattern in the weave to eliminate irregular, blurred portions or similar defects. That is to say, the contrasting ombré shades of two adjoining colors in the weave will always be in proper register during the repeat of the pattern throughout the length of the goods being woven, there being no chance of one bobbin being exhausted while running with a certain shade and the related bobbin in the next shuttle continuing to run with the inappropriate shade of filling registering with the shade of the replenished bobbin. While the error in matching or registering the ombré shades of the colors may be very slight with respect to the different time of replenishing the filling in any two related shuttles as due to the disparity in the length of yarn on these particular bobbins, on the other hand the disparity will be multiplied as more bobbins are changed and it is for this reason that it is essential to replenish the bobbins in both related shuttles upon the indication of the exhaustion of filling in either one. The present invention therefore constitutes an important improvement in the art of weaving jacquard or similar patterns in ombré or like effects and the improvement may be applied to other purposes beyond that contemplated in the present description.

The present specification illustrates a preferred embodiment of the device by way of example, but is to be understood that the construction and arrangement of its mechanism may be varied considerably and its method of application to the loom may also be altered without departing from the broad principle of the invention. Therefore, without limiting ourselves to the exact form of construction as herein shown and described, we claim:

1. A filling-replenishing mechanism for multi-shuttle looms comprising a filling-detector operative upon the depletion of the filling in one shuttle to replenish the filling in this shuttle, and means set in operation by the same action of the filling-detector to change the filling in an associated shuttle when this latter shuttle is called.

2. A filling-replenishing mechanism for

jacquard and dobby looms having means operative upon the indication of depletion of filling in one shuttle to replenish the filling in another associated shuttle when this latter shuttle is called, and means set in operation by the same filling indication to replenish the filling in the first shuttle when that shuttle is called again.

3. A filling-replenishing mechanism for multi-shuttle looms comprising means for indicating depletion of filling in any one shuttle, means operative therefrom to replenish the filling in this shuttle, and means set in operation by the same action of the indicating-means to change the filling in the next shuttle called.

4. In a filling-replenishing mechanism for box-motion looms, the combination of a filling-detector for indicating filling depletion in the running shuttle, means operative therefrom to replenish the filling in the next shuttle called, and means set in operation by the same action of the filling-detector to thereafter replenish the filling in the first shuttle when that shuttle is called again.

5. In an automatic loom, the combination of a multi-cell magazine for containing a supply of bobbins carrying different kinds of filling, a feeler for indicating depletion of filling in the running shuttle, means operative therefrom upon the indication of depletion of filling in the running shuttle to change the filling in the next shuttle called, and means set in operation by the same action of the feeler to change the filling in the first shuttle when that shuttle is called again.

6. In a color-control for the filling-replenishing mechanism of automatic looms, the combination of a feeler for indicating depletion of the filling in the running shuttle, means for transferring fresh bobbins to the shuttles, means rendered operative by a single action of the feeler to set the transfer-means to transfer bobbins to two or more shuttles upon the depletion of the filling in one of them, and means actuated upon the calling of each of said shuttles to operate the transfer-means.

7. In a color-control for the filling-replenishing mechanism of automatic looms, the combination with a multi-color magazine for holding a supply of bobbins carrying filling of different colors, a feeler for indicating exhaustion of the filling in the running shuttle, means for transferring fresh bobbins to the shuttles in accordance with the color running therein, means to selectively operate said transfer-means from a single indication of the feeler to successively transfer bobbins to any two shuttles carrying certain colors of filling appearing in register in the pattern being woven, and means to operate said transfer-means as each of said two shuttles is first called after a single indication of the feeler.

8. In a color-control for the filling-replen-

ishing mechanism of automatic looms, the combination of a multi-color magazine for containing bobbins carrying filling of different colors, a feeler for indicating depletion of the filling in the running shuttle, means for selectively transferring bobbins to the shuttles in accordance with the color running therein, means actuated from a single indication of the feeler to set the transfer-mechanism to operate on a plurality of associated shuttles, and means for actuating the transfer-means as each of the associated shuttles is called.

9. In a multi-color control for the filling-replenishing mechanism of automatic looms, the combination of a magazine for containing a plurality of sets of bobbins carrying filling of different colors, means for selectively transferring the bobbins from the magazine to the respective shuttles, a feeler for indicating depletion of the filling in the running shuttle, means caused to be actuated by the feeler to initiate the operation of the transfer-means, means actuated by the initial indication of the feeler to continue the operation of the transfer-means to selectively transfer a bobbin to the shuttle carrying its respective color, and means set in operation by the same indication of the feeler to subsequently transfer another bobbin to a shuttle carrying its color immediately the latter is called.

10. In a filling-replenishing for automatic looms, the combination of a magazine containing separate sets of bobbins carrying filling of different colors, means for transferring the bobbins from the magazine to the respective shuttles carrying filling of the same color, a feeler for indicating depletion of the filling in the running shuttle, means set in action by the feeler to transfer a bobbin to the next shuttle called, and means cooperating therewith to thereafter transfer a bobbin to the first shuttle when the latter is called again.

11. In a device of the type specified, the combination of a magazine for containing a plurality of sets of bobbins carrying different kinds of filling, transfer-means operative in connection with each set of bobbins to transfer the appropriate type of bobbin to the running shuttle, a feeler for indicating depletion of the filling in the running shuttle, means operated by the movement of the feeler indicating on the bobbin in the running shuttle to actuate the transfer-means to transfer a bobbin to any particular shuttle, and means to subsequently transfer a bobbin to the shuttle in which the filling has indicated depletion.

12. In a device of the type specified, the combination of a magazine for holding a plurality of sets of bobbins carrying filling of different kinds, transfer-means for transferring the bobbins to the respective shuttles

carrying the same kind of filling, a feeler for indicating depletion of the filling in the running shuttle, means operated by a single indication of the feeler to set the transfer-means to selectively transfer bobbins to two successively called shuttles, and means to operate the transfer-means when the respective shuttles are called.

13. In a device of the type specified, the combination of a magazine for supplying bobbins carrying different kinds of filling, control means for selectively releasing the bobbins from the magazine in accordance with the kind of filling in the running shuttle, a feeler for indicating depletion of the filling in the running shuttle, means actuated by a single indication of the feeler to cause the control-means to select a plurality of bobbins for delivery from the magazine, and means for successively transferring all of the several bobbins selected by the control-means to their respective shuttles immediately the latter become active.

14. In a device of the type specified, the combination with the box-motion of a multi-color loom, of a magazine for holding bobbins carrying filling of different colors, means operated in synchrony with the box-motion to selectively transfer the proper bobbin from the magazine to the running shuttle in accordance with the color of filling therein, a feeler for indicating depletion of filling in the running shuttle, means set in motion by a single indication of the feeler to set the transfer-means to transfer bobbins to two or more selected shuttles, and means actuated by the calling of said shuttles to complete the transfer of the bobbins thereto as said shuttles are placed in operation by the box-motion.

15. In a device of the type specified, the combination of a magazine having a plurality of cells for containing bobbins carrying different kinds of filling, means for releasing the bobbins singly from the magazine, a control-lever for selectively operating the releasing-means, a feeler for indicating depletion of filling in the running shuttle, means caused to be operated from the feeler to actuate the control-lever to initiate the operation of the releasing-means for a plurality of cells, and means for continuing the operation of the releasing-means to deliver the several bobbins to the transfer-means for transfer to the different shuttles as each of the latter becomes operative.

16. In a device of the type specified, the combination of a magazine having a plurality of cells for containing bobbins carrying different kinds of filling, means for transferring the bobbins from the magazine to the shuttles to replenish the filling therein, means operating in connection with each cell of the magazine to deliver the different bobbins to the transfer-means, a feeler for indicating depletion of the filling in the running shuttle,

means caused to be actuated from the feeler to initiate the operation of the bobbin-releasing means for a plurality of cells, and means for continuing the operation of the releasing means as each of several shuttles is called to successively transfer the appropriate kind of bobbin thereto.

17. In a device of the type specified, the combination of a magazine having a plurality of cells for containing bobbins carrying different kinds of filling, cradles for sustaining the bobbins in their cells, slides connected to operate the cradles to release the bobbins from their cells, a rockable lever for operating the slides, means adapting said lever to operate on a plurality of slides to initiate their action in releasing the bobbins from their cells, a feeler for indicating depletion of the filling in the running shuttle, means connecting the feeler to operate the control-lever, and means for transferring the bobbins to the shuttles as they are successively delivered from the cells of the magazine.

18. In a device of the type specified, the combination of a magazine having a plurality of cells for containing bobbins carrying different kinds of filling, cradles for sustaining the bobbins in the cells, slides for operating the cradles to release the bobbins from the cells, projections on said slides, a rockable lever for engaging the projections to raise and lower the slides, a latch on said lever adapted to engage the projections on a plurality of slides to move the latter in one direction, and means on the lever for engaging a single projection to move only one slide in the opposite direction.

19. In a device of the type specified, the combination of a magazine having a plurality of cells for containing bobbins carrying different kinds of filling, cradles for sustaining the bobbins in their cells, slides for operating the cradles to release the bobbins from their cells, a pair of fingers on each slide, a rockable-lever having an arm adapted to engage with the fingers on the slides, a latch on said arm adapted to engage across the fingers on a plurality of slides, and means for rocking the lever to raise and lower the slides.

20. In a device of the type specified, a magazine having a plurality of cells for containing bobbins carrying different kinds of filling, cradles for sustaining the bobbins in their cells, a slide connected to each cradle to operate the latter and provided with fingers projecting from its side, a rockable lever having an arm adapted to engage with the fingers on the slides to selectively move the latter to actuate the cradles, a latch on said arm adapted to engage with the fingers on a plurality of slides to cause the latter to be moved to initiate the release of a plurality of bobbins, and means to actuate the lever to cause it to move a plurality of the slides into position whereby each of said slides will

thereafter be moved to actuate its cradle to release a bobbin from the cell controlled thereby.

In testimony whereof we affix our signatures.

WILFRID J. LEMIEUX.
JAMES HOOD.
